Patented Apr. 3, 1928.

UNITED STATES PATENT OFFICE.

ARTHUR T. YODER, OF MOSINEE, WISCONSIN.

CYLINDER PAPER-MAKING MACHINE.

Application filed May 27, 1926. Serial No. 111,953.

This invention relates to cylinder paper making machines and more particularly to a silencer roll as applied to the vat of a cylinder machine.

5 It is an important object of this invention to provide a silencer roll, or perforated drum, for use with cylinder machines, whereby boiling currents of stock may be quieted in their flow to the cylinder mold, thus permitting the machine to be run at 10 higher speeds with the formation of a better sheet of paper.

It is a further important object of this 15 invention to provide a cylinder mold vat wherein all of the stock going to the cylinder mold is caused to pass through a silencer roll for the purpose of quieting the eddy currents and effecting a uniform distribution of the stock.

20 Other and further important objects of this invention will be apparent from the disclosures in the specification and the accompanying drawings.

This invention (in a preferred form) is 25 illustrated in the drawings and hereinafter more fully described.

On the drawings:

Figure 1 is a fragmentary broken top plan view of a cylinder mold vat showing the installation of a silencer roll of my invention. 30

Figure 2 is a sectional view taken on line II-II of Figure 1.

The reference numeral 1 indicates a cylinder mold vat, preferably made of heavy 35 lumber tongued and grooved as at 2 and constructed in the usual manner, common in cylinder paper making machine installations. Said vat 1 resembles a rectangular shaped box having a bottom wall 3, a back wall 4, and side walls 5 of the same height as said back wall 4. A vertical partition 6, also preferably formed of heavy lumber tongued and grooved and spaced from the rear walls 4 to form a head box 21, extends 40 transversely of said vat 1 and terminates a short distance below the top of said vat walls 5. A second transverse partition 7, shaped approximately in an arc of a circle, is spaced from said vertical partition 6 by 45 means of a horizontal piece of timber 8 joined to the top of said partition 6 and to the rear wall of said partition 7. The upper end of said partition 7 extends a short distance vertically above the horizontal timber 8 to form a baffle 9. Said partition 7 thus 50 forms with the front portion of the vat 1,

a cylinder mold vat 10 in which a cylinder mold 11 is adapted to be rotatably mounted. Said cylinder mold 11 is of the usual construction and is covered with a wire facing 60 12 on which the web of paper is adapted to be formed.

As is usual, stock enters the space 21 between the rear wall 4 and the vertical partition 6, and passes up over the baffle 9 into the cylinder mold vat 10, where due to suction created within the cylinder mold the pulp fibres are deposited upon the surface of the wire 12, the greater portion of the water in the stock passing through the wire. In 70 my present construction I mount a silencer roll 13, comprising a perforated metal drum, between the horizontal timber 8 and the top of the vat walls 5 and in front of the baffle 9, in such a way that all of the stock must pass through the perforations 14 of said silencer roll. The journals 15 of said silencer roll 13 extend through stuffing boxes 16 in the side walls 5, and are rotatably mounted 75 in bearings 22. One of said journals 15 is provided with a coupling 17 connected with a driving shaft 18 and a suitable driving mechanism such as a speed reducer 19 and a motor 20. The silencer roll 13 may be revolved at any suitable speed and in either direction, depending on the practical results obtained.

It will be noted that the diameter of the silencer roll 13 is preferably exactly equal to the vertical distance between the upper face 90 of the timber 8 and the top edge of the side walls 5 in order to insure the passing of all of the stock through said silencer roll 13 in its flow to the cylinder vat 10. It would of course be possible to extend the walls of the 95 vat above the top of the silencer roll 13 but in that case an over flow should be provided to prevent the stock from flowing over the top of said silencer roll 13.

One of the principal advantages of the 100 construction above described is that the silencer roll 13 quiets and silences the boiling and eddying of the stock in its flow to the cylinder vat 10. The silencer roll insures a uniform velocity of stock across the width 105 of the vat, thus tending toward a better formation on the wire 12 and also permitting the cylinder mold 11 to be run at higher speeds. One of the principal difficulties in 110 making paper on a cylinder machine is that unless the cylinder mold is run at a comparatively low speed the sheet of paper formed is

liable to be weak in the across-the-machine direction due to the fact that the individual fibres tend to lie longitudinally, that is, in the direction of travel of the wire. The silencer roll 13 not only quiets the violent motions of the stock but also tends to cross the fibres in their passage through the apertures 14 of the silencer roll. This crossing of the fibres effects the formation of a much stronger sheet than can be produced without the use of a silencer roll. It should be further noted that the baffle 9 serves to maintain a uniform head of stock in front of the cylinder vat 10 and it also serves further to produce an even flow of stock to the cylinder mold.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. In a cylinder paper machine, a vat for the cylinder mold having a transverse partition terminating below the side walls of said vat and in front of said mold and a perforated drum mounted transversely of said vat completely filling the space between the top of said partition and the top of the vat side walls, whereby all of the stock must pass through said perforated drum in its flow to the cylinder mold.

2. In a cylinder paper machine, a vat for the cylinder having a transverse partition therein defining a head box for stock and a cylinder vat for the cylinder mold, a vertical baffle formed on said partition and a silencer roll positioned ahead of said baffle and extending above the same, whereby all of the stock passing to said cylinder vat is forced to pass through said silencer roll.

In testimony whereof I have hereunto subscribed my name.

ARTHUR T. YODER.
